US0D1061132S

(12) **United States Design Patent** (10) **Patent No.:** **US D1,061,132 S**
(45) **Date of Patent:** **** Feb. 11, 2025**

(54) **CHOPPER**

(71) Applicants: **Zuwu Lin**, Zhuhai (CN); **Leilei Wang**, Yiyang (CN); **Xueli Zhuo**, Leizhou (CN)

(72) Inventors: **Zuwu Lin**, Zhuhai (CN); **Leilei Wang**, Yiyang (CN); **Xueli Zhuo**, Leizhou (CN)

(**) Term: **15 Years**

(21) Appl. No.: **29/804,043**

(22) Filed: **Aug. 18, 2021**

(30) **Foreign Application Priority Data**

May 24, 2021 (CN) 202130312266.0

(51) **LOC (15) Cl.** **31-00**
(52) **U.S. Cl.** **D7/384**

(57) **CLAIM**

The ornamental design for a chopper, as shown and described.

DESCRIPTION

FIG. 1 is a perspective view of the chopper showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view of thereof; and,

FIG. 7 is a bottom plan view of thereof.

The broken lines shown in the drawings represent portions of the chopper that form no part of the claimed design.

1 Claim, 7 Drawing Sheets
